UNITED STATES PATENT OFFICE.

HERBERT EDWIN JACKSON AND JOHN ALEXANDER ANDERSON, OF BARROW-IN-FURNESS, ENGLAND, ASSIGNORS TO WILLIAM H. JACKSON, OF BRADFORD, ENGLAND.

DEVICE FOR FACILITATING LIGHTING OF CYCLE OR OTHER LAMPS.

SPECIFICATION forming part of Letters Patent No. 608,154, dated July 26, 1898.

Application filed December 3, 1897. Serial No. 660,672. (No model.) Patented in England October 16, 1897, No. 23,879.

To all whom it may concern:

Be it known we, HERBERT EDWIN JACKSON and JOHN ALEXANDER ANDERSON, subjects of the Queen of Great Britain and Ireland, residing at 233 Whittaker street, Dalton Road, Barrow-in-Furness, England, have invented certain new and useful Improvements in Devices for Facilitating the Lighting of Cycle or other Lamps, (for which we have obtained a patent in Great Britain, No. 23,879, dated October 16, 1897;) and we do hereby declare the following to be a full, clear, and exact description of the invention, such as will enable others skilled in the art to which it appertains to make and use the same.

Our invention relates to a new and improved device for facilitating the lighting of cycle lamps and the like, the object being to enable the lamp (in the case of a cycle-lamp) to be lighted without it being necessary for the rider to dismount from the machine or being compelled to open the lamp in any way. Moreover, it enables the lamp to be readily lighted in windy weather; and the means we employ to this end is very simple and effective.

In order that our invention may be fully understood, we will now proceed to describe same, with reference to the accompanying drawings, in which—

Figure 1 is a side elevation of a cycle-lamp, showing the application thereto of our improved automatic lighting device. Fig. 2 is a back view of the automatic lighting device detached and drawn to a considerably-enlarged scale. Fig. 3 is a front view of same, and Fig. 4 is a vertical section. Fig. 5 is a plan of the device.

According to our invention we provide an automatic lighting device *d*, Fig. 1, said device comprising a hollow conical body *a*, Figs. 2 to 4, which is cut away at one side, the cut-away portion or opening *c* being preferably covered with a plate *b* of flexible or springy metal or material and which upon its inner surface is preferably roughened or serrated, and behind this plate *b* is arranged a

stiffer strip *c*, of steel or other suitable material, designed to keep the plate *b* closely against the sides of the lighting device and in such a manner that upon a match being forced through the body of same it is ignited by the friction set up as the head of the match passes beneath the plate *b* and through the conical body.

The hollow cone *a* is circular in cross-section, and its sides are formed on converging curves, which are much sharper at the blunt end portion *b'* of the cone. These sides guide the match so that it can only project centrally of the cone and at the exact spot where it can ignite the lamp-wick to the best advantage, and the match is prevented from missing the wick.

The automatic lighting device is inserted in the side, back, or other suitable part of the lamp-body in such a manner that its inner end is in close proximity to the wick, so that by passing a match through same it is ignited, as hereinbefore described, when the light can be readily applied to the wick without opening any part of the lamp, thus rendering it easy for the lamp to be lighted in positions or situations where it would be practically impossible if the ordinary means had to be adopted.

As a slight modification of our invention instead of employing in connection with the plate *b* a strip such as *c* said plate *b* may be made sufficiently strong and springy of itself as to render unnecessary the use of such a strip.

Although we have illustrated our invention as applied to a cycle-lamp, we wish it to be understood that we do not restrict ourselves to this one particular application of the invention, as it may be used in connection with carriage or other lamps for which it is suitable and where its application would be attended with advantageous results.

Having now described our invention, what we claim as new, and desire to secure by Letters Patent, is—

An igniting device, comprising a hollow cone circular in cross-section and having a

blunt-pointed end portion provided with an opening on one side, the sides of the cone being formed on curves which are sharper at the said end portion than at the body of the
5 cone and which constrain the match to project centrally of the cone, and a spring-controlled friction-plate normally covering the said opening, substantially as set forth.

In testimony whereof we affix our signatures in presence of two witnesses.

HERBERT EDWIN JACKSON,
JOHN ALEXANDER ANDERSON.
